ANIMATABLE TOY

Jacques Martial, Great Neck, and Lincoln L. Ciampa, New York, N. Y., assignors to United States Electric Mfg. Corp., New York, N. Y., a corporation of New York.

Application December 19, 1951, Serial No. 262,383

13 Claims. (Cl. 46—118)

1

This invention relates to animatable toys.

It is an object of the present invention to provide a device of the character described which is attractive and interesting to children.

It is another object of the present invention to provide a device of the character described which has a novel mechanism whereby a sound will be produced, an appendage move and a portion of the toy light up when the toy is actuated by a wearer.

It is another object of the present invention to provide an animatable toy of the character described which is of simple and light construction.

It is another object of the present invention to provide an animatable toy of the character described which is easily and inexpensively manufactured.

It is another object of the present invention to provide an animatable toy of the character described which is simply operated.

It is another object of the present invention to provide an animatable toy of the character described which is rugged so that it will stand up under rough use from children.

Other objects of the invention will in part be obvious and in part will be pointed out hereinafter.

The invention accordingly consists in the features of construction, combinations of elements and arrangements of parts which will be exemplified in the devices hereinafter described and of which the scope of application will be indicated in the appended claims.

In the accompanying drawings in which is shown one of the various possible embodiments of my invention,

Fig. 1 is a front view of an animatable toy constructed in accordance with the present invention;

Fig. 2 is a side view of said toy;

Fig. 3 is a back view of the toy;

Fig. 4 is a sectional view taken substantially along the line 4—4 of Fig. 2;

Fig. 5 is a sectional view taken substantially along the line 5—5 of Fig. 4;

Fig. 6 is a sectional view taken substantially along the line 6—6 of Fig. 4;

Fig. 7 is a fragmentary sectional view taken substantially along the line 7—7 of Fig. 4; and

Fig. 8 is a fragmentary rear perspective view of the lapel pin.

Referring now in detail to the drawings, the reference numeral 10 denotes an illuminatable animatable toy embodying the invention.

2

The toy is hollow and comprises a carrier, e. g. a rearing horse 12, on which is seated a rider, e. g. a cowboy 14, appropriately garbed in western attire.

5 The toy includes a casing 16 having a front half 18 and a back half 20. The front half constitutes a front wall 22 fashioned into the shape of a horse having one foreleg 24, a figurine of a cowboy being seated on the horse. The casing includes no

10 rear leg for the horse and no visible arm for the cowboy. The front half of the casing has a peripheral flange 26 extending backwardly so that said front half constitutes a shell in which the working elements of the toy can be disposed. The back half of the casing constitutes a rear cover for the toy and matches the contour of the rim 26 of the peripheral flange.

15 Openings 30 for eyes are provided in the head 32 of the cowboy, and eyes 34 are disposed within

20 the head. A slot 36 is fashioned in the horse's head between the ears and eyes. Said slot slants upwardly away from the rider. A circular hole 38 is formed in the figurine of the rider at the shoulder 40. An arm 42 is provided having a hollow

25 tube 44 adapted to rotatably fit in the hole in the casing. Said arm carries a simulated gun 46 formed integrally with the hand 48. When the toy is not being operated, the gun lies below the slot in the horse's head. Said gun is so disposed that when the arm is raised to its highest position the gun will lie in line with the slot; optionally it may overlap the slot partially.

30 A hole 50 is provided in the bottom of the peripheral flange at the horse's hip 52 for receiving the visible rear leg 54 of the horse.

35 The casing is fabricated from some light material such as sheet metal or plastic.

30 Pursuant to the present invention when the horse's rear leg is pushed upwardly the cowboy's eyes will roll, his arm will rise until the gun is in line with the slot, at the moment the gun is in line with the slot a light will shine through the slot so that it appears that the gun has fired, and at the same time a click will emanate from the 45 pin so that the illusion of a gun having fired is complete.

Turning now to the mechanism by which the above-described operation is effected, the movable rear leg of the horse is integral with an L-shaped actuator 56 disposed inside the casing, said actuator being attached to the proximal end 58 of the leg at the lower surface 60 of the short bar 62 of the L. The actuator is movable between a rest position and a fully operative position. The long bar 64 of the L is disposed ad-

jacent an inner wall 68 of the peripheral flange, and the short bar lies athwart the lower end of the casing. The wall 68 adjacent which the long bar of the L is disposed is the part of the flange 26 which forms the top of the horse behind and under the rider. The wall 70 opposite which the long bar of the actuator is disposed forms the undersurface of the horse.

Riblike guides 72, 74, 76 for a battery 78 and for the actuator are provided on the inner surface of the front half of the casing. The bottom end 80 of the battery rests on the top surface 82 of the short bar of the actuator, and said battery extends along part of the hollow cylinder 84 formed by the inner wall of the portion 86 of the front half of the casing forming the horse's body. The rear cover of the casing and the aforementioned guides for the battery hold the battery snugly in place preventing front and back movement of the same. The long leg of the actuator and the guides snugly hold the battery against sidewise movement. Thus, the battery is guided for up and down motion.

The guide 76 for the actuator is located in the wall 68 adjacent which the long leg of the actuator is disposed and comprises a step 90 on which the front edge of said leg rests and also includes a portion 92 set back from the step and extending rearwardly from the same. The side of the long leg of the actuator is disposed against said portion. The actuator is constrained against front and back movement by said step, the slot for the leg, and the back cover part of the casing. The actuator is constrained against lateral movement by the battery and rearwardly extending portion of the actuator guide, and also by the slot for the leg. Accordingly, the actuator is guided for up and down movement in the casing.

Above the top of the battery another guide 94 is located, said guide being adapted to receive the shank 96 of a flashlight bulb 98. The bulb is screwed into one end of an electrically conductive compression spring 100 the other end of which is fitted about the top 102 of an uninsulated battery cup. The top 104 of the bulb envelope abuts the top inner surface 106 of the peripheral flange of the front half of the casing. The rear cover and the bulb guide hold the bulb firmly in place. The top of the battery and the bottom of the bulb shank have aligned central terminals 108, 110. When the actuator is at rest, these terminals are out of contact. When the actuator is moved upwardly, it will raise the battery until the central terminals come into contact and the bulb lights, this being the fully operative position of the actuator. When the actuator is released, the compression spring separates the central terminals, thereby breaking the contact. The spring forces the actuator into its rest position in which it contacts the lower end of the casing. Separate means, however, may be provided as described below to return the actuator and battery to rest position.

Near the top of the long bar of the actuator two projections 112, 114 are provided extending away from the cavity of the horse's body. These two projections form a groove 116. The tube on the movable arm of the rider has two longitudinal slots 118, 120. When the arm is in rest position, one of said slots 118 faces the groove in the actuator.

Means is provided to transform the linear motion of the actuator into rotary motion of the tube and thus of the arm. Said means com-

prises a pintle 122 having a flat thin tongue 124 extending radially therefrom and terminating short of the ends thereof. The pintle fits into the bore 126 of the tube and is permanently secured therein, e. g. by adhesive, with the tongue extending through the slot. The distal end 128 of the tongue fits into the groove in the actuator, and thus when the actuator is raised the pintle is rotated and with it the arm. Since the tongue overlies the hole in which the tube is rotatable and since the tongue is permanently secured in the tube, the tongue prevents the tube and thus the arm from being pulled out of the casing. The rear end of the pintle is journaled in a hole 130 in the rear cover.

The arm is so oriented with respect to the slot that when the former has been rotated to the position it occupies when the actuator has been moved to its fully operative position, the arm is so disposed with respect to the slot in the horse's head that the gun is in line with said slot.

The rider's eyes are disposed on a plate 132 secured to the front edge of an arm 134 integral with a pin 136. Said pin has a tongue 137 similar to that of the pintle. Means is provided in the front part of the casing upon the inner surface thereof and in the rider's head to rotatably receive the front end of said pin whereby rotation of the pin will swing the eyes into and out of registry with the eye-openings. Said means constitutes a cup-shaped boss 138. The tongue of said pin fits into the second slot 120 in the tube. Thus, when the actuator is moved and the tube rotated, the tongue will also be rotated whereby the plate carrying the eyes will move and the illusion of the eyes rolling will be imparted to the figurine. The rear cover of the casing has a hole 139 rotatably receiving the rear end of the pin when the cover is put on.

Depending upon the position of the second slot in the tube and the position of the eyes on the plate connected to the pin, said eyes will either be out of sight when the actuator is at rest and come into sight when the actuator is being operated or will start in sight and be rolled out of sight or will be partially in sight all of the time and merely roll when the actuator is moved between its two positions.

To supply a click simulating the noise of the gun, a leaf spring 140 with a depression 142 is provided. A rearwardly extending abutment 144 is located in the rider's head, and the spring is fitted between the abutment and the peripheral flange. In order to fit the spring in place it must be slightly bent, and the force of the spring trying to return to unstressed position will press the portions of the spring on each side of the abutment against the inner wall of the peripheral flange of the front half of the casing, thus holding the spring in place. One end of the spring extends over the top of the long bar of the actuator. When the actuator is moved upwardly as far as it will go, the spring is distorted and the depression will turn inside out with a clicking sound. Said depression is disposed between the abutment and the actuator. The spring may be shaped so that the end of the spring which abuts the actuator when the same is operated will abut the actuator when the latter is at rest. The leaf spring will then be stressed as soon as the actuator is moved, and thus the former will serve to return the actuator to rest position when the actuator is released, and gravity will draw the battery down with the

actuator should the compression spring become defective.

The above mechanism is completely operated from the actuator which in turn is operated by the rear leg of the horse; when the actuator is operated, contact between the bulb and the battery is not made until the actuator is at its fully operative position, nor will the click emanate until such time. The arm and eyes, however, will move throughout the upward movement of the actuator and will also move when the actuator returns to its rest position. Thus, the eyes will have rolled before the click and flash of light, and the weapon will reach firing position level with the slot as the click and flash occur.

In several corners of the back edge of the peripheral flange in the front half of the casing platforms 145 are provided recessed frontwardly from said edge. The rear cover rests upon these.

The rear cover 20 is in two sections 146, 148. Section 146 covers the back of the horse, and section 148 covers the back of the rider. The sections fit against each other edgewise, section 146 being provided with a step 150 on the side edge of the front surface thereof. Section 148 has a matching step 152 on the side edge of its rear surface. The section 146 will aid in holding section 148 in place when the former is in place on the front half of the casing because the step of section 146 overlies that of section 148.

Two projections 154 extend rearwardly from the front half of the casing, said projections having inwardly extending portions 156. Under each portion a transverse groove 158 is formed.

A pin 160 is provided having a base portion 162 adapted to lie flat across both sections of the rear cover. The base of the pin is about as long as the distance between the projections. Integral with the base are two rearwardly extending reaches 164, said reaches extending further rearwardly than the front surface of the grooves of the portions 156. Then the reaches extend towards each other a distance less than the length of portions 156. Each reach has an arm 166 extending sidewise and frictionally fitting a groove 158. One arm terminates in an open loop 168. The other arm terminates in a spring bar extending towards the loop and adapted to disengageably fit the loop. The pin may be snapped from between the projections when it is desired to open the toy. When snapped into place, the spring will hold the sections of the rear cover against the front half of the toy and will also serve as a detachable fastener for the toy to a garment.

It thus will be seen that there is provided a device which achieves all the objects of the invention and is well adapted to meet the conditions of practical use.

As various possible embodiments might be made of the above invention, and as various changes might be made in the embodiment above set forth, it is to be understood that all matter herein described, or shown in the accompanying drawings, is to be interpreted as illustrative and not in a limiting sense.

Having thus described the invention, there is claimed as new and desired to be secured by Letters Patent:

1. An animatable toy comprising a hollow opaque object constituting a figurine of a rider on a carrier, an appendage for said figurine, means to mount said appendage on said figurine,

for movement between a rest position and an operative position; a simulated weapon carried by said appendage, means to produce a noise associated with the weapon, light-producing means interiorly of said object, said last-named means including an opening in the object, said opening being located at the point on the object which the weapon is adjacent when the appendage is in operative position, a mechanism for the toy, said mechanism including means to move the appendage and thus the weapon from its rest to its operative position, means to actuate the noise-producing means when the appendage is in its operative position, and means to operate the light-producing means when the appendage is in its operative position, the various means of the mechanism functioning in conjunction with each other, means to operate the mechanism from the outside of the toy, and means to return it to its inoperative position.

2. An animatable toy comprising a hollow opaque object constituting a figurine of a rider on a carrier, an appendage for said figurine, means to mount said appendage on said figurine for movement between a rest position and an operative position; a simulated weapon carried by said appendage, means to produce a noise associated with the weapon, light-producing means interiorly of said object, said last-named means including an opening in the object, said opening being located at the point on the object which the effective end of the weapon is adjacent when the appendage is in operative position, a mechanism for the toy, said mechanism including means to move the appendage and thus the weapon from its rest to its operative position, means to actuate the noise-producing means when the appendage is in its operative position, and means to operate the light-producing means when the appendage is in its operative position, the various means of the mechanism functioning in conjunction with each other, means to operate the mechanism from the outside of the toy, and means to return it to its inoperative position.

3. An animatable toy comprising a hollow opaque object constituting a figurine of a rider on a carrier, an appendage for said figurine, means to mount said appendage on said figurine for movement between a rest position and an operative position; a simulated weapon carried by said appendage, eyes in the head of the rider, means to mount said eyes for movement in said head, means to produce a noise associated with the weapon, light-producing means interiorly of said object, said last-named means including an opening in the object, said opening being located at the point on the object which the weapon is adjacent when the appendage is in operative position, a mechanism for the toy, said mechanism including means to move the appendage and thus the weapon from its rest to its operative position, means to move said eye-mounting means, means to actuate the noise-producing means when the appendage is in its operative position, and means to operate the light-producing means when the appendage is in its operative position, the various means of the mechanism functioning in conjunction with each other, means to operate the mechanism from the outside of the toy, and means to return it to its inoperative position.

4. An animatable toy comprising a hollow opaque object constituting a figurine of a rider on a carrier, an appendage for said figurine, means to mount said appendage on said figurine,

for movement between a rest position and an operative position, a simulated weapon carried by said appendage, means to produce a noise associated with the weapon, a mechanism for the toy, said mechanism including means to move the appendage and thus the weapon from its rest to its operative position, and means to actuate the noise-producing means when the appendage is in its operative position, the various means of the mechanism functioning in conjunction with each other, means to operate the mechanism from the outside of the toy, and means to return it to its inoperative position.

5. An animatable toy comprising a hollow opaque object constituting a figurine of a rider on a carrier, an appendage for said figurine, means to mount said appendage on said figurine for movement between a rest position and an operative position a simulated weapon carried by said appendage, light-producing means interiorly of said object, said last-named means including an opening in the object, said opening being located at the point on the object which the effective end of the weapon is adjacent when the appendage is in operative position, a mechanism for the toy, said mechanism including means to move the appendage and thus the weapon from its rest to its operative position, and means to operate the light-producing means when the appendage is in its operative position, the various means of the mechanism functioning in conjunction with each other, means to operate the mechanism from the outside of the toy, and means to return it to its inoperative position.

6. A toy as set forth in claim 1 wherein the mounting means for the appendage constitutes a hollow tube on the appendage and a shoulder opening in the figurine rotatably receiving the tube, said tube having a slot parallel to its longitudinal axis, and wherein the means to move the appendage constitutes an actuator translatable between two positions, a pintle, and a tongue integral with said pintle, said actuator having a slot to receive said tongue, said pintle being permanently secured in the hollow of said tube, and said tongue extending through the slot of said tube and over the inside of the figure, whereby linear movement of the actuator is transformed into rotary movement of the tube.

7. A toy as set forth in claim 1 wherein the noise-producing means constitutes a leaf spring secured at one end to the object, said spring having a depression therein intermediate its ends, and wherein the means to actuate the noise-producing means comprises an actuator movable between a fully operative and a rest position, the free end of said spring being in the path of travel of the actuator, whereby motion of the actuator to its fully operative position will flex the spring, the spring and location of the actuator being adjusted so that the depression will turn inside out when the actuator is at its fully operative position.

8. A toy as set forth in claim 1 wherein the light-producing means includes a cell having a side terminal and at its front a center terminal, a lamp having a side terminal and at its rear a center terminal, and a conductive coil spring electrically and physically connecting the side terminal of said cell to the side terminal of said lamp, the center terminal of the cell being out of contact with the center terminal of said lamp in the inoperative position of the toy, and wherein the means to operate the light-producing means constitutes an actuator movable between

75 a fully operative and a rest position, said actuator having a seat on which the rear of the battery cell is disposed, and a stop for the top of the light bulb, said center terminals contacting each other when the actuator is in its fully operative position and the coil spring compressed.

9. An animatable toy comprising a hollow opaque object constituting a figurine of a rider on a carrier, an appendage for said figurine, means to mount said appendage on said figurine for movement between a rest position and an operative position, a simulated weapon carried by said appendage, and means to move the appendage and thus the weapon from its rest to its operative position, said last-named means comprising a projection on said appendage, an opening in said figurine rotatably receiving said projection, an element on said projection, said element being disposed within the figurine, and means to move said element, said moving means constituting a part of the carrier, engaging said element and having portions within and without the toy.

10. An animatable toy comprising a hollow opaque object constituting a figurine of a rider on a carrier, an appendage for said figurine, means to mount said appendage on said figurine for movement between a rest position and an operative position, a simulated weapon carried by said appendage, light-producing means interiorly of said object, said last-named means including an opening in the object, said opening being located at the point on the object which the effective end of the weapon is adjacent when the appendage is in its operative position, means to operate the light-producing means when the appendage is in its operative position, and means to move the appendage and thus the weapon from its rest to its operative position, said last-named means comprising a projection on said appendage, an opening in said figurine rotatably receiving said projection, an element on said projection, said element being disposed within the figurine, and means to move said element, said moving means constituting a part of the carrier, engaging said element and having portions within and without the toy, the means to operate the light-producing means being operative from the means to move the appendage.

11. An animatable toy comprising a hollow opaque object constituting a figurine of a rider on a carrier, an appendage for said figurine, means to mount said appendage on said figurine for movement between a rest position and an operative position, a simulated weapon carried by said appendage, means to produce a noise associated with the weapon, light-producing means interiorly of said object, said last-named means including an opening in the object, said opening being located at the point on the object which the weapon is adjacent when the appendage is in operative position, means to actuate the noise-producing means and light-producing means when the appendage is in its operative position, means to move the appendage and thus the weapon from its rest to its operative position, said last-named means comprising a projection on said appendage, an opening in said figurine rotatably receiving said projection, an element on said projection, said element being disposed within the figurine, and means to move said element, said moving means constituting a part of the carrier, engaging said element and having portions within and without the toy, said means to operate the noise-producing means and light-

producing means being operative from the means to move the appendage.

12. An animatable lapel pin comprising a hollow opaque object having a front half and rear cover and constituting a figurine of a rider on a carrier, an appendage for said figurine, means to mount said appendage on said figurine for movement between a rest position and an operative position, a simulated weapon carried by said appendage, light-producing means interiorly of said object, said last-named means including an opening in the object, said opening being located at the point on the object which the effective end of the weapon is adjacent when the appendage is in its operative position, means to operate the light-producing means when the appendage is in its operative position, and means to move the appendage and thus the weapon from its rest to its operative position, said last-named means comprising a projection on said appendage, an opening in said figurine rotatably receiving said projection, an element on said projection, said element being disposed within the figurine, means to move said element, said moving means constituting a part of the carrier, engaging said element and having portions within and without the lapel pin, the means to operate the light-producing means being operative from the means to move the appendage, and means to fix the pin to an object, said means also serving to maintain the cover on the front half.

13. An animatable toy comprising a hollow opaque object having a front half and rear cover and constituting a figurine of a rider on a carrier, an appendage for said figurine, means to mount said appendage on said figurine for movement between a rest position and an operative position, a simulated weapon carried by said appendage, light-producing means interiorly of said object, said last-named means including an opening in the object, said opening being located

at the point on the object which the effective end of the weapon is adjacent when the appendage is in its operative position, means to operate the light-producing means when the appendage is in its operative position, and means to move the appendage and thus the weapon from its rest to its operative position, said last-named means comprising a projection on said appendage, an opening in said figurine rotatably receiving said projection, an element on said projection, said element being disposed within the figurine, means to move said element, said moving means constituting a part of the carrier, engaging said element and having portions within and without the toy, the means to operate the light-producing means being operative from the means to move the appendage, and means to fix the toy to an object, said last-named means comprising a bar extending across and contacting the rear cover and disengageably engaging projections extending from the rear of the front half whereby said last-named means also serves to maintain the cover on the front half, said member having at one end a rearwardly extending reach which terminates in an open loop and having at the other end an elongated element extending up to and through said loop.
